5 Claims. (Cl. 189—37)

This application is a division of my copending application Ser. No. 8,077 filed February 11, 1960, now abandoned.

When, in the construction of reinforced concrete floors, the molds used are made entirely of wood, the correct positioning of a mold and of its stays requires numerous adjustments and forms a lengthy and difficult operation, since it is necessary to provide for alignment of the different sections of the operative surface of the mold which should remain in the same horizontal plane. In order to eliminate such difficulties, it is common practice to resort to metal girders or beams formed by a single body or by a main body with one or two extensions sliding telescopically inside the main body and of which the upper flat flanges, engaging the edge boards rigid with the walls or the like bearing members for the bays, carry the mold or the previously prepared hollow bricks or like elements, whereby it is possible to obtain the desired level of the floor through the very rigidity of the beams.

But this known system has a serious drawback which is the fact that the girders are too heavy and expensive even though they carry without substantially bending the weight of the floor although they rest only through their ends. Now, whereas concrete sets in a few days and may immediately be lifted, provided the floor which is not yet bestowed with the desired resistance is held on auxiliary intermediate supports, it is impossible to remove the girders which carry the floor before a complete hardening of the concrete and total solidification of the floor into a rigid unit, which requires a long period of time.

The long time during which the girders are to be held in position for each floor during execution of the latter thus leads the contractor who is working on different sites to have a large number of such girders, which corresponds to a large investment of capital and, consequently, the use of such girders, in spite of their advantages, is often considered by the contractor as too expensive and therefore of no practical interest.

My invention has for its object a novel structure of such girders with a view to cutting out such drawbacks by allowing the removal of the girders as soon as the concrete has set, so as to be immediately available for further use.

According to my invention, there is provided longitudinally of each girder, whether simple or compound, at least one gap in the upper flange forming the supporting plane for the hollow flooring elements, said gap being obtained through a drop in the level of said supporting plane over a predetermined area so as to form underneath the general level of said supporting plane at least one free space through which it is possible to insert a transverse plank. Said plank, which should be suitably supported by stays to either side of the girder, is adapted to carry the section of the mold or of the hollow elements lying above it. As soon as the concrete has set, it is possible to remove the girder, the floor being carried then at one or more points of its length by said plank or planks which are removed only after complete solidification of the flooring concrete incorporating the hollow elements.

If the girder is constituted by a plurality of sections, say a main section with an extension, the area of the

2

carrying surface which is to lie at a lower level may be provided in any of such sections, for instance in the main section, or else, in its extension.

In the case of large spans, it may be necessary to resort to two main sections interconnected by an intermediate extension, and in this case, the extension should have a reduced height, so that the space extending between the two main sections may form above the upper flange of the intermediate connecting extension the desired empty space

10 which is to be engaged by the transverse plank.

I have illustrated, in the accompanying drawing and by way of a mere exemplification, two preferred embodiments of my invention. In said drawing:

FIGS. 1 to 3 illustrate a girder including a main section provided with an extension of a reduced height sliding telescopically inside the main section at one end of the latter.

FIG. 1 is a side view of said girder,

FIG. 2 is a cross-section through line II—II of FIG. 1, and

FIG. 3 is a cross-section through line III—III of FIG. 1 showing the girder together with the floor constituted by hollow bricks laid over said girder and by the concrete cast over same.

FIG. 4 is a lateral elevational view of an arrangement wherein the girder includes two sections interconnected by an extension or intermediate connecting section of a reduced type.

Turning to FIGS. 1 to 3, the beam P is constituted at 30 least near one of its ends in a manner such that it forms a guiding slideway for an extension R of a reduced height, either of said sections P and R or both being provided with bolts or the like clamping means for rigidly securing said two sections together. To this end, the girder P includes,

35 for instance, between its lower U-shaped flange 1, its upper box-shaped flange 5 and the vertical or oblique struts forming two laterally arranged sets 2a—2b, an empty central space forming a longitudinal slideway inside which may be slidably engaged the extension R formed simply by two T-shaped flanges 3 and 3' and an interconnecting central trellis-work 4. The upper flange 5 of the girder is constituted, in the case illustrated, by a tubular or box-shaped member, the upper surface of which is flat and is adapted to carry the mold or the hollow elements and is provided at different points of its length with bolts 6 which may be screwed into the actual flange or, better still, inside nuts 6" welded to the edges of perforations extending through the lower wall of the box-shaped flange, so as to allow the free passage of the bolt shanks. The

50 heads 6' of said bolts allow operating the latter and the part played by the latter consists, upon unscrewing of the bolts, in engaging clampingly the upper flange 3' of the extension R, so that the latter may be aligned with the main section of the girder, after which the main section

55 of the girder and its extension are locked together. According to the invention, the upper flange of the main section is interrupted towards the middle of its length or at several suitably spaced points, if the flange is sufficiently long, so as to leave an empty space above a portion p of a reduced height of said section, whereby it is

60 possible to introduce across the gap thus formed a transverse plank M resting on the upper surface of said portion p which is at a lower level than the remainder of the upper surface of the main section. The upper surface of the transverse plank is flush with the general upper surface of the flange 5, as clearly apparent from inspection of FIG. 1. Said plank is subsequently stayed laterally of the girder, as shown at E before said girder is removed,

65 while the plank should remain stayed in position until the floor has reached its final solidification stage. The difference in level between the plane carrying the mold or

hollow members and the upper surface of the extension R which is held by a bent T-shaped member on the corresponding lateral board may be compensated also by the insertion of planks.

FIG. 3 shows the general arrangement of the hollow bricks B or the like elements carried by a series of girders P associated with a stayed transverse plank M, the hollow elements being capped by a layer of concrete C.

In the embodiment of my invention illustrated in FIG. 4, which is more particularly of interest in the case of large spans, the girder includes a plurality of sections, to wit: two main interconnected sections, the total length of which is adjustable by means of an intermediate connecting extension. The two main sections P1 and P2 show, throughout their length or at least near one end, the particular structure allowing them to act as a longitudinal slideway, while the connecting section L is similar to or identical with the above-described extension R, its height being less than that of the main girder sections P1 and P2 so that, when its ends engage the slideways in the sections P1 and P2, as illustrated in FIG. 4, an empty space remains above said extension, which allows the insertion of a transverse carrying plank M.

In the case where the gap between the two main sections P1 and P2 is larger than the breadth of a plank, I may lay, next to the first plank, one or two further planks, as shown at m and m', which are removed as soon as the girder has been removed.

Having described my invention, I claim:

1. A metallic beam assembly for temporarily carrying elements of a composite concrete floor, comprising a pair of metallic beams, one said beam being hollow and the other said beam sliding within said one beam, said one beam having a top member terminating downwardly in an under surface, said other beam having a top surface spaced a substantial distance below said under surface thereby to support a first plank on said top surface with the plank extending transversely of the beam assembly, said beam assembly having means defining an upwardly opening recess spaced a substantial distance from said other beam, the bottom of said recess being at about the same level as said top surface thereby to support a second plank on said bottom in parallelism to said first plank.

2. A temporary support for composite concrete flooring, comprising a plurality of spaced parallel beam assemblies, each beam assembly comprising a pair of metallic beams, one said beam of each assembly being hollow and the other said beam of each assembly sliding within said one beam, each said one beam having a top member terminating downwardly in an under surface, each said other beam having a top surface spaced a substantial distance below said under surface of the associated said one beam, and a plank extending transversely of and bridging across said beam assemblies and resting on said top surfaces.

3. A support as claimed in claim 2, the top of the plank being substantially flush with the tops of said top members.

4. A temporary support for composite concrete flooring, comprising a plurality of spaced parallel beam assemblies, each beam assembly comprising three metallic beams, two said beams of each assembly being hollow and in longitudinal alignment with each other and having their adjacent ends spaced apart a substantial distance and a third said beam of each assembly sliding within said two beams of the associated assembly, said two beams of each said beam assembly having top members terminating downwardly in an under surface, each of said third beams having a top surface spaced a substantial distance below the under surface of the associated said top members, and a plank extending transversely of and bridging across said beam assemblies and resting on said top surfaces.

5. A support as claimed in claim 4, the top of the plank being substantially flush with the tops of said top members.
